COMBINED TOOTHBRUSH AND TUMBLER HOLDER

Sidney J. Shames, 57 Holly Place, Briarcliff Manor, N.Y.
10510, and Harold Shames, 5 Agnes Circle, Ardsley,
N.Y. 10502

Filed Mar. 31, 1971, Ser. No. 130,058

Term of patent 14 years

Int. Cl. D6—06

U.S. Cl. D6—92

FIG. 1

FIG. 2

FIG. 3

FIG. 4.

FIG. 5.

FIG. 1 is a top plan view of a combined toothbrush and tumbler holder embodying our new design;

FIG. 2 is a front perspective view thereof;

FIG. 3 is a side elevational view thereof;

FIG. 4 is an enlarged cross-sectional view taken substantially along line 4—4 of FIG. 2; and

FIG. 5 is an enlarged cross-sectional view taken substantially along line 5—5 of FIG. 1.

The broken line representation of a support bracket in FIG. 3 is for purposes of illustration only.

We claim:

The ornamental design for a combined toothbrush and tumbler holder, as shown and described.
